CLAIM

The ornamental design for an orthodontic clasp bracket, as shown and described.

DESCRIPTION

FIG. 1 is a cross sectional view taken along lines 1—1 of FIG. 6 illustrating a flattened portion of an omega loop wire that is formable into a circular loop;

FIG. 2 is a perspective view of an orthodontic clasp bracket showing my new design;

FIG. 3 is a cross sectional view taken along lines 3—3 of FIG. 7 illustrating an omega loop wire and a marginal ridge wire as they are arranged inside the silver solder;

FIG. 4 is a top plan view thereof;

FIG. 5 is a left elevation view thereof;

FIG. 6 is a front elevation view thereof;

FIG. 7 is a right elevation view thereof; and,

FIG. 8 is a bottom plan view thereof.
